(57) **CLAIM**

The ornamental design for a sighting apparatus for golf, as shown and described.

DESCRIPTION

FIG. 1 is a front perspective view of a sighting apparatus for golf, showing my new design;

FIG. 2 is an enlarged-scale perspective view thereof from an upper oblique vantage point;

FIG. 3 is a front elevational view thereof;

FIG. 4 is a side elevational view of a magnet-provisioned side thereof;

FIG. 5 is a side elevational view of the opposite side;

FIG. 6 is a top plan view thereof;

FIG. 7 is a bottom plan view thereof;

FIG. 8 is a rear elevational view thereof;

FIG. 9 is an enlarged-scale section view taken along line IX-IX in FIG. 2; and,

FIG. 10 is a front perspective view comparable to FIG. 1 except on an enlarged scale and showing an alternate example of a manner of use thereof.

The broken lines and areas shaded in section line in the drawing represent environmental subject matter that forms no part of the claimed design.

1 Claim, 8 Drawing Sheets
